UNITED STATES PATENT OFFICE.

CHARLES F. MASSEY, OF CHICAGO, ILLINOIS, ASSIGNOR TO C. F. MASSEY COMPANY,
OF CHICAGO, ILLINOIS, A CORPORATION OF ILLINOIS.

LAMP-SUPPORTING STRUCTURE.

1,085,144

Specification or Letters Patent. Patented Jan. 27, 1914.

Application filed January 24, 1913. Serial No. 743,997.

To all whom it may concern:

Be it known that I, CHARLES F. MASSEY, a citizen of the United States, and resident of Chicago, in the county of Cook and State of Illinois, have invented certain new and useful Improvements in Lamp-Supporting Structures, of which the following is a specification.

My invention relates to lamp supporting structures, particularly to structures used for street illuminating purposes. Such structures usually comprise a post from which extend lamp supporting brackets.

Among the important objects of my invention are to provide an arrangement in which a lamp supporting frame is detachable with reference to its supporting post so that the post and frame can be more readily built up of concrete or other cementitious material and more readily shipped; to provide simplified means whereby the lamp supporting frame may be quickly and readily applied to the post when the post is set up for service; to provide a simplified arrangement which will adapt the lamp supporting frame for reversible application to the post in order that lamps may be supported in upright position or in depending position; to provide improved construction and arrangement which will allow connections to be readily made between main current supply conductors running through the post and leads extending through the supporting frame to the lamps; and in general to provide more efficient and desirable construction and arrangement in lamp supporting structures.

In the accompanying drawings Figure 1 is an elevational view of a lamp supporting structure, with some of the lamp structures removed; Fig. 2 is a plan view with some of the lamp structures removed; Fig. 3 is a sectional view taken on plane 3—3, Fig. 1; Fig. 4 is a sectional view taken on plane 4—4, Fig. 2, and Fig. 5 is an elevational view of the upper end of the post with the lamp supporting structure removed.

Referring to the drawings a post 10 is built up of concrete and has an enlarged base 11, and an enlarged head 12, there being a polygonal upward extension 13 from the head for receiving a lamp supporting structure. This lamp supporting structure comprises a hub 14 and arms 15 extending laterally therefrom. The passageway 16

through the hub is polygonal to receive the extension 13 so that the hub may be slipped downwardly about the extension and seat against the head 12 of the post. Extending through each arm is a pipe 17, the inner ends 60 of these pipes terminating at the hub passageway 16 and the outer ends terminating, as shown in the figures, at the upper sides of the ends of the arms. The ends of the arms serve to support lamp holding devices 18 65 which are secured to the arms in register with the outlets of the ducts 17. The holders 18 will support each a lamp 19, and if desired, a globe 20. In the arrangement shown the lamp supporting frame has been 70 applied to support the lamp structures in upright position but it is evident that this frame can be reversed so that the lamp structures will be supported in depending position, as shown in dotted lines. In either 75 position the frame receives the extension 13 and seats securely against the head 12.

A conduit pipe 21 extends through the post and receives the current supply conductors which connect with the street mains 80 in any desired manner. As shown, a cross pipe 22 extends through the base of the post and is threaded at its protruding ends for insertion in the street duct or pipe. In order that connections may readily be made between the main supply conductors 23 and leads 23' extending through the pipes 17 to the lamp structures, the extension 13 is hollow to provide a compartment 24 and lateral passageways 25, which passageways 90 register with the inner ends of the pipes 17. When the lamp supporting frame is set on the post the ends of the main supply conductors and the leads can be made in the compartment 24 or these ends can be extended out through the upper end of the hollow extension and made outside of the post, and then put back into the compartment 24. A center light 26 may be provided with its holder 27 seated on the end of the 100 extension 13 to communicate with the compartment 24.

The lamp supporting structure and the post are preferably each constructed integral of concrete or other cementitious material and the pipes 17 besides acting as conduits for the leads to the illuminants also serve to reinforce the concrete. Likewise the pipe 21 which conveys the current supply conductors from the base of the post to 110

the compartment 24 will serve to reinforce the concrete. Other or additional reinforcing material may of course be provided.

By having the lamp supporting structure detachable, shipment can be more readily made and furthermore when the post is installed the lamp supporting frame can be easily applied in position either to support the lamps upright or in position to support the lamps in depending arrangement. No extraneous securing means are necessary as the hub of the supporting frame snugly receives the extension 24 and securely seats on the head of the post.

15 I do not of course desire to be limited to the exact construction and arrangement shown and described except as specified in the claims which are as follows:

1. In a lamp supporting structure, the combination of a post having a reduced neck extending upwardly therefrom and having a shoulder at the base of the neck, said neck being polygonal and hollow, and its outer faces being vertical, a hub having a vertical polygonal bore for slipping over said neck to engage with either end against said shoulder, arms extending radially from said hub and supporting light fixtures at their ends, passageways through the sides of said neck to the interior thereof, and ducts through said hub and arms extending from the light

fixtures and terminating at said passageways.

2. In a lamp supporting structure, the combination of a post of cementitious material having a reduced hollow neck extending upwardly therefrom and having a supporting shoulder at the base of the neck, a lamp supporting frame built integral of cementitious material and comprising a hub and arms extending radially therefrom for supporting light fixtures, said neck being polygonal and having its outer faces vertical and parallel and said hub having a polygonal bore for receiving the neck whereby said hub may be slipped over the neck to engage with either end against said shoulder, a conduit pipe leading upwardly through the post and terminating in the hollow neck, the walls of said neck having passageways therethrough, and conduit pipes extending through said arms and hub through which wires may be extended from the hollow neck to the lamp fittings.

In witness whereof, I hereunto subscribe my name this 20th day of January, A. D., 1913.

CHARLES F. MASSEY.
